SIGNAL TRANSLATING SYSTEM

Harold M. Lewis, Great Neck, N. Y., assignor to
Hazeltine Corporation, a corporation of Delaware

Application June 28, 1938, Serial No. 216,200

12 Claims. (Cl. 178—7.2)

This invention relates to television systems and more particularly to improved television video-frequency signal-translating systems.

In accordance with present television practice, a transmitted signal comprises picture- or video-frequency components representative of varying light values in successive areas of an image being transmitted and synchronizing-signal components which correspond to initiations of successive lines and fields in the scanning of the image. The video-frequency components occur during the trace-scanning periods, while the synchronizing-signal components occur during the retrace-scanning periods. Between the trace-scanning periods, the signal is blocked out, that is, it includes block-out components which ordinarily have amplitude values extending outside of the amplitude range of the video-frequency components on the black side of the axis of the modulation wave. There is usually also developed at the transmitter a unidirectional voltage which corresponds to the average background illumination of the scene. While this voltage is lost when the signal is passed through alternating current amplifiers, the signal at all times includes a component from which the unidirectional voltage representative of background illumination may be derived.

There is provided at the receiver a signal-reproducing device, such as a cathode-ray tube, in which a scanning beam is deflected to scan, in series of parallel lines or fields, a fluorescent screen upon which the image of the transmitted scene is reconstructed. The synchronizing-signal components of the received signal are utilized to control the scanning apparatus at the receiver so as to synchronize its operation with that of similar apparatus at the transmitter, while the intensity of the cathode ray is controlled by the video-frequency signal components, as well as the unidirectional background-illumination voltage, thereby to reconstruct the scene.

One of the essential functions which must be performed in a television system is the establishment of a fixed signal level corresponding to black. Due to the fact that the block-out components of the signal ordinarily extend substantially beyond the amplitude range of the video-frequency signal on the black side of the signal axis, the peak values of these block-out components do not correspond to the black level of the signal unless the amplitude of such components is limited; that is, unless portions thereof beyond the black level are suppressed. Moreover, it has been found difficult to limit such a

television signal including such components by devices heretofore utilized without substantially distorting the wave form of the signal. In general, the grid-voltage plate current characteristic of a tube designed to operate over a wide grid swing, that is, to accommodate a relatively large input-signal amplitude, has a curvature near cutoff which is very gradual relative to that of the corresponding characteristic of a tube designed to operate over a small grid swing. In the latter type of tube, however, this range of curvature bears the same relationship to the normal amplitude range of the input signal as in the case of the first-mentioned tube. Hence, the same percentage of signal distortion results from the use of either type of tube if the signal amplitude is adjusted to a range corresponding to the normal operating range of the tube. However, if a large amplitude signal is applied to a tube designed for a relatively small grid swing, the tube has a relatively sharp characteristic with respect to the large amplitude signal, but it can repeat only a small part of the signal.

It is an object of the present invention, therefore, to provide an improved television video-frequency signal-translating system, whereby portions of the signal beyond a predetermined value on one side of its axis may be substantially suppressed without distorting the resultant signal.

A further object of the invention is to provide a system of the character described, whereby the black level of the signal may be readily set without distortion of the useful portions of the signal.

In accordance with the invention, a television video-frequency signal-translating system for suppressing portions of a translated video-frequency signal of lesser amplitude values than that corresponding to a predetermined shade value thereof comprises a first channel including an output circuit for translating the signal with one polarity, together with means for applying to the channel the video-frequency signal including background components. This first channel includes means for providing a stabilized signal in its output circuit. A second channel is provided including an output circuit for translating the signal with opposite polarity and means are provided for applying the above-mentioned video-frequency signal to the second channel. The second channel also includes means for providing a stabilized signal of opposite polarity in its output circuit and limiting means for passing only portions of the translated signal of lesser amplitude value than that corresponding to the

above-mentioned shade value. Means are provided for combining the oppositely-poled unidirectional signal outputs of the above-mentioned channels including the background components 5 of the translated signals, whereby the lesser amplitude value portions of the translated signal are at least partially suppressed. For example, the portion of the signal beyond the value on one side of its axis corresponding to black may be 10 suppressed so as to establish a predetermined black level for the signal, that is, to set the tone of black.

Moreover, the signal to be translated may include background-illumination components as 15 well as the video-frequency components, and these components may be represented by the peak value of the signal on one side of its axis; for example, the peak value of the block-out signal components on the black side of the axis. In such a 20 case, in accordance with the present invention, there may be provided rectifying means for deriving from the signal a background-illumination control-bias voltage representative of the background illumination, that is, proportional to the 25 said peak value of the signal, and means for applying the derived bias voltage to the two channels of the system, thereby to stabilize the signal inputs thereto.

For a better understanding of the invention, 30 together with other and further objects thereof, reference is had to the following description taken in connection with the accompanying drawing, and its scope will be pointed out in the appended claims.

35 In the accompanying drawing, Fig. 1 is a circuit diagram, partially schematic, of a television transmitting system including circuits embodying the present invention, while Fig. 2 is a graph representing certain operating characteristics of 40 the system of Fig. 1, to aid in the understanding of the invention.

Referring now more particularly to Fig. 1 of 45 the drawing, there is illustrated a television transmitting system comprising a signal generator 10, which may be of conventional design and include the usual cathode-ray signal-generating tube and scanning elements. For the purpose of developing scanning voltages or currents for the generator 10, there are provided a line-frequency 50 saw-tooth wave generator 11 and a field-frequency saw-tooth wave generator 12, the output circuits of these generators being connected to the scanning elements of the signal generator 10 in the usual manner. In order to block out 55 the scanning ray of the generator 10 during retrace scanning periods, there is provided a block-out wave generator 13 having its output circuit suitably connected to the generator 10. For providing impulses to suppress undesirable signal 60 impulses during retrace scanning periods and to ensure proper form of the modulation signal to be developed, there is provided a pedestal-impulse generator 14. A synchronizing signal generator 15 is also provided for developing synchronizing- 65 signal components.

For the purpose of synchronizing the generators 11-15, inclusive, there is provided a timing-impulse generator 16 coupled to the input circuits of the generators 11-15, inclusive. The timing-impulse 70 generator 16 is preferably stabilized by means of a connection 17 to a suitable source of periodic voltage, for example, the power supply circuit or the synchronizing voltage source of a motion picture mechanism, where such is employed.

Connected in cascade to the output circuit of the signal generator 10, in the order named, are a first video-frequency amplifier 18, a second video-frequency amplifier 19, which embodies the present invention and will be hereinafter described in more detail, a third video-frequency amplifier 20, a modulator 21 and associated carrier-frequency oscillator 22, a power amplifier 23, and an antenna system 24, 25, all constructed and arranged according to conventional practice. The 10 output circuit of the pedestal generator 14 is coupled to the video-frequency amplifier 18, while the output circuit of the synchronizing-signal generator 15 is coupled to the video-frequency amplifier 20. Suitable means (not shown but 15 which may be considered as included in the signal generator 10) are also provided for developing a unidirectional background-illumination voltage and applying it to the amplifier 18.

Neglecting for the moment the details of operation of the video-frequency amplifier 19, the system just described comprises the elements of a television transmission system of conventional design and, the various parts thereof being illustrated schematically and being of any well-known construction, a detailed description of its operation is unnecessary. Briefly, however, the image of a scene to be transmitted is focused on the target of the signal generator 10. Scanning currents or voltages are applied to the scanning elements of the generator 10 to supply electric fields which serve to deflect the scanning ray horizontally and vertically, thereby to scan successive series of parallel lines, or fields, upon the target. The deflecting currents or voltages and, hence, 30 the scanning fields are of the well-known saw-tooth wave form, providing relatively slow linear trace and rapid retrace scansions. Block-out impulses developed by the generator 13 are applied to the signal generator 10 to suppress or 35 block out the scanning beam during retrace portions of the scanning cycles, while pedestal impulses developed by the generator 14 are applied to the amplifier 18 to suppress surges which occur in the signal. The timing impulses developed by 40 the generator 16 are applied to the generators 11-15, inclusive, to lock these generators in synchronism.

The photosensitive elements of the target of the signal generator 10 are electrically affected to an 50 extent dependent upon the varying values of light at the corresponding incremental areas of the image focused thereon so that, as the scanning beam scans the target, a video-frequency voltage of correspondingly varying amplitude is developed 55 in the output circuit of the generator 10 and applied to the video-frequency amplifier 18. The unidirectional background-illumination voltage, which is developed by suitable means included in the generator 10, is also applied to the amplifier 18, as well as the pedestal impulses developed by 60 the generator 14. Thus, the video-frequency components, blockout components, unidirectional background components, and pedestal impulses are all amplified and mixed in the amplifier 18 65 and are thereupon applied to the video-frequency amplifier 19, wherein they are translated in accordance with the present invention and from which they are applied to the video-frequency amplifier 20. The synchronizing impulses developed by the generator 15 are mixed with the modulation signal in the amplifier 20 and the resultant modulation signal is thereupon supplied to the modulator 21, wherein it is impressed upon the carrier wave generated by the oscillator 22. 70 75

The modulated-carrier signal is then delivered to the power amplifier 23 for amplification and is impressed upon the antenna system 24, 25 to be broadcast.

5 Referring now more particularly to the amplifier 19 embodying the present invention, for the purpose of establishing a fixed predetermined black level for the modulation signal, this amplifier comprises a plurality of vacuum amplifier tubes 26, 27, and 28, which are preferably of the pentode type, having high internal impedance. The tubes 26 and 27 are connected in cascade to provide a first signal-translating channel, while the tube 28 provides a second signal-translating 10 channel connected in parallel with the first channel, the two channels having substantially equal mutual conductance characteristics.

15 The signal input grid of the tube 26 is coupled to the output circuit of the video-frequency amplifier 18 by means of a coupling condenser 29 and leak resistor 30, while the anode circuit of this tube includes a load resistor 31. The signal-input grid-cathode circuit of the tube 27 is, in turn, connected across the resistor 31 by way of 20 a coupling condenser 32 and leak resistor 33. The signal-input grid of the tube 28 is connected directly in parallel with that of tube 26. The anode circuits of the tubes 27 and 28 are connected in parallel and include a common load 25 resistor 34 and choke 35 across which the input circuit of the amplifier 20 is connected, as shown. Operating potentials for the tubes 26, 27, and 28 are supplied to their screens from suitable sources indicated at +Sc, and to their anodes by way of 30 their load circuits from suitable sources indicated at +B. A source of adjustable-bias voltage is provided for the tube 28, for example, by means of a battery 40 included in its cathode circuit.

35 For the purpose of reinserting the unidirectional or background-illumination component of the signal, which is lost in transmission through alternating current couplings, such as the condensers 29 and 32, that is, for stabilizing the 40 translated signals at a level corresponding to a predetermined shade value thereof, there are provided diode rectifiers 36 and 37 connected with opposite polarities across the input circuits of the amplifiers 26 and 28 and the amplifier 27, respectively, and in parallel with the leak resistors 30 and 33, the rectifiers 36 and 37 thus comprising 45 means for deriving from the translated signal a background-illumination control voltage proportional to the peak value of the signal on one side of its alternating current axis. The diodes 36 and 37 are also connected in series with sources of 50 suitable biasing potential, indicated by the batteries 38 and 39, respectively.

55 Referring now to the operation of the system of the present invention, it will first be noted that the peaks of the block-out portions of the waves, occurring during retrace-scanning periods and having lesser amplitude values than the video-frequency components thereof, as applied to the tubes of the amplifier 19 are at all times at 60 the same level, that is, the signals are stabilized. This is due to the fact that the background illumination or unidirectional component of the signal is reinstated by the action of the diodes 36 and 37. More particularly, in the absence of a 65 signal the batteries 38 and 40 serve to bias the tube 28 near cutoff, while the battery 39 biases the tube 27 near its cutoff point. The diodes 36 and 37 derive from the signal outputs of the amplifiers 18 and 26, respectively, negative and positive unidirectional voltages, respectively, equal to

70 the peak values of the signal on the black side of its axis, which voltages appear across the leak resistors 30 and 33, which also comprise the rectifier load resistors. These unidirectional voltages are thus applied to the control grids of the tubes 5 26 and 28 and tube 27 in opposition to the fixed biases from the batteries 38 and 39, respectively. The resultant video-frequency signals applied to the control grids of the tubes, therefore, are of a stabilized wave form including the unidirectional 10 background-illumination components as well as the video-frequency or high-frequency components with the negative peaks of the signal, as stated above, all at the same level. The tube 26 simply serves to reverse the polarity of the signal 15 so that it is applied in opposite senses to the tubes 27 and 28.

15 The details of operation of the system of the present invention may best be explained with reference to the curves of Fig. 2. In this figure, 20 the abscissae represent grid voltages and the ordinates, plate current. Curve A represents the grid-voltage plate current characteristic of the tube 27, the signal voltage as applied to this tube being illustrated by curve A_g and having the lowest amplitude value of the amplitude range of the video-frequency components corresponding to black. Curve B, on the other hand, represents the similar characteristic of the tube 28, while the signal voltage as applied 25 to this tube is also illustrated by curve A_g , its abscissae scale being displaced and running in an opposite sense relative to that of curve A to account for the reversal of polarity of the signal input to the tubes 27 and 28. The curves are 30 plotted in this manner so as more clearly to illustrate the conditions resulting from reversing the polarities of the signals, as applied to the tubes 35 27 and 28. In curve A_g the portions indicated at v represent the video-frequency components, and 40 the portions indicated at b represent the block-out components.

45 It will be noted from the curves that the tube 27 is designed to operate with a relatively wide grid swing and is biased so as to operate within its cutoff limits and primarily over the linear portion of its characteristic, thereby to develop in its output circuit a signal of which the video-frequency components are undistorted. The tube 28, on the other hand, is designed to operate over 50 a relatively narrow grid swing and has a relatively sharper cutoff and is biased well below its cutoff point so that only a portion of the applied signal beyond a predetermined value on the side of its axis corresponding to black is repeated in 55 its output circuit.

55 The effective grid-voltage plate current characteristic of the combination of tubes 27 and 28, connected as shown and with the signal applied to their grids with opposite polarities, is represented 60 by the curve C. From this curve it will be seen that, in the vicinity of the block-out components b , the slope of the curve, that is, the transconductance of the combination, is substantially zero so that the block-out components are not 65 repeated in the common output circuit. Thus, the present invention provides an arrangement whereby the advantage of sharp limitation of the signal is obtained without sacrificing linearity of transmission of the portion of the wave which it 70 is desired to pass. Curve C_0 represents the wave form of the resultant current in the common output circuit of the tubes 27 and 28. It will be seen from this curve that the portion of the signal beyond the predetermined value, for example, 75

the value corresponding to black, on the black side of the axis of the signal is substantially suppressed, while the video-frequency portion which is repeated is substantially undistorted. In other words, the black level for the signal is set without distortion of the useful portions of the signal.

More clearly to illustrate the advantages achieved by the arrangement of the present invention, curve D, shown at the left of Fig. 2, 10 represents the output current as it would appear if the limiting action were obtained without utilizing tube 28; that is, simply by increasing the negative bias of the tube 27 so as to operate it beyond cutoff, as indicated by curve B_g. In this 15 case the wave form of the signal output is substantially distorted as indicated at the portions d.

In certain instances it may be desirable to limit the signal above the block-out portions so as to set the black level at a different value, thereby to 20 set the black level of the combined signal at any desired tone value of the signal. For the purpose of adjusting the black level or tone of black in the signal, as developed by the system of the present invention, it is only necessary to adjust 25 the bias on the tube 28, for example, by adjusting the battery 40. Curve C₁ illustrates the effective grid-voltage plate current characteristic for the combination for an increase in the negative bias of the tube 28 and the curve C₂ illustrates the 30 resultant signal output of tubes 27 and 28 for this condition.

In summary, therefore, it is seen that the television video-frequency signal-translating system of Fig. 1 suppresses the blacker-than-black portions of a translated video-frequency signal, these portions being of lesser amplitude values than a predetermined shade value of the signal, that is, the black level thereof. The system comprises a first channel including tubes 26 and 27 for translating with one polarity a signal including video-frequency and background components and for providing a stabilized signal in the output circuit thereof. The signal also comprises a second channel, including tube 28, for translating the 45 same signal with a polarity opposite to that of the first channel and for providing a stabilized signal at the output circuit thereof. As used in this specification, the phrase "translating with opposite polarity" means that, for signal inputs to the 50 two channels of the same polarity, signal outputs of different polarities are obtained from the respective channels. It is also seen that a limiting means, specifically, tube 28 biased by battery 40, is included in the second channel for passing only 55 portions of the signal of lesser amplitude value than that of the predetermined shade value, that is, for passing only the blacker-than-black portions of the signal. Means are also provided for combining the oppositely-poled signal outputs of 60 the channel so that the blacker-than-black portions of the signal, or the said portions of lesser amplitude values, are at least partially suppressed.

While there has been described what is at present considered to be the preferred embodiment of this invention, it will be obvious to those skilled in the art that various changes and modifications may be made therein without departing from the invention, and it is, therefore, aimed in the appended claims to cover all such changes 70 and modifications as fall within the true spirit and scope of the invention.

What is claimed is:

1. A television video-frequency signal-translating system for suppressing portions of a translated video-frequency signal of lesser amplitude

values than that corresponding to a predetermined shade value thereof comprising, a first channel including an output circuit for translating a signal with one polarity, means for applying to said channel a video-frequency signal including background components, said channel including means for providing a stabilized signal in said output circuit, a second channel including an output circuit for translating said signal with opposite polarity, means for applying said video-frequency signal to said second channel, said second channel including means for providing a stabilized signal of opposite polarity in its output circuit and limiting means for passing only portions of said signal of lesser amplitude value than that corresponding to said predetermined shade value, and means for combining the oppositely-poled unidirectional signal outputs of said channels including background components, whereby said lesser amplitude value portions of said signal are at least partially suppressed.

2. A television video-frequency signal-translating system for suppressing portions of a translated video-frequency signal of lesser amplitude values than that corresponding to a predetermined shade value thereof comprising, a first channel including an output circuit for translating a signal with one polarity, means for applying to said channel a video-frequency signal including background components, said channel including means for providing a stabilized signal in said output circuit, a second channel including an output circuit for translating said signal with opposite polarity, means for applying said video-frequency signal to said second channel, said second channel including means for providing a stabilized signal of opposite polarity in its output circuit and limiting means for passing only portions of said signal of lesser amplitude value than that corresponding to said predetermined shade value, said two channels having substantially equal mutual conductance characteristics, and means for combining the oppositely-poled unidirectional signal outputs of said channels including background components, whereby said lesser amplitude value portions of said signal are at least partially suppressed.

3. A television video-frequency signal-translating system for suppressing portions of a translated video-frequency signal of lesser amplitude values than that corresponding to a predetermined shade value thereof comprising, a first amplifier including an output circuit for translating a signal with one polarity, means for applying to said amplifier a video-frequency signal including background components, said amplifier including means for providing a stabilized signal in said output circuit, a second amplifier including an output circuit for translating said signal with opposite polarity, means for applying said video-frequency signal to said second amplifier, said second amplifier including means for providing a stabilized signal of opposite polarity in its output circuit and limiting means for passing only portions of said signal of lesser amplitude value than that corresponding to said predetermined shade value, and means for combining the oppositely-poled unidirectional signal outputs of said channels including background components, whereby said lesser amplitude value portions of said signal are at least partially suppressed.

4. A television video-frequency signal-translating system for suppressing portions of a translated video-frequency signal of lesser amplitude

values than that corresponding to a predetermined shade value thereof comprising, a first channel including an output circuit for translating a signal with one polarity, means for applying to said channel a video-frequency signal including background components, said channel including means for providing a stabilized signal in said output circuit, a second channel including an output circuit for translating said signal with opposite polarity, means for applying said video-frequency signal to said second channel, said second channel including means for providing a stabilized signal of opposite polarity in its output circuit and limiting means for passing only portions of said signal of lesser amplitude value than that corresponding to said predetermined shade value, means for adjusting said limiting means to adjust said predetermined value, and means for combining the oppositely poled unidirectional signal outputs of said channels including background components, whereby said lesser amplitude value portions of said signal are at least partially suppressed.

5. A television video-frequency signal-translating system for suppressing portions of a translated video-frequency signal of lesser amplitude values than a predetermined shade value thereof comprising a first channel having a given cutoff characteristic for translating with one polarity a unidirectional video frequency signal including background components, and a second channel for translating said signal with opposite polarity and having a relatively sharper cutoff characteristic and including limiting means for passing only portions of said signal of lesser amplitude value than said predetermined shade value, means for stabilizing the signal inputs to said channels, and means for combining the oppositely poled signal outputs of said channels, whereby said lesser value portions of said signal are at least partially suppressed.

6. A television video-frequency signal-translating system for suppressing portions of a translated video-frequency signal of lesser amplitude values than a predetermined shade value thereof comprising a first channel for translating with one polarity a signal including video-frequency and background-illumination components, a second channel for translating said signal with opposite polarity and including limiting means for passing only portions of said signal of lesser amplitude value than said predetermined shade value, means for deriving from said background-illumination components of said signal a unidirectional-bias voltage representative of background illumination, means for utilizing said bias voltage to stabilize the signal inputs to said channels, and means for combining the oppositely poled signal outputs of said channels, whereby said lesser value portions of said signal are at least partially suppressed.

7. A television video-frequency signal-translating system for suppressing portions of a translated video-frequency signal of lesser amplitude values than a predetermined shade value thereof comprising a first channel for translating with one polarity a signal including video-frequency and background-illumination components represented by the peak value of the signal on one side of its axis, a second channel for translating said signal with opposite polarity and including limiting means for passing only portions of said signal of lesser amplitude value than said predetermined shade value, rectifying means for deriving from said signal a background-illumina-

tion control-bias voltage proportional to said peak value of said signal, means for applying said bias voltage to said channels to stabilize the signals passed thereby, and means for combining the oppositely poled signal outputs of said channels, whereby said lesser value portions of said signal are at least partially suppressed.

8. A television video-frequency signal-translating system for suppressing portions of a translated video-frequency signal of lesser amplitude values than a predetermined shade value thereof comprising a first channel for translating with one polarity a signal including video-frequency and background-illumination components represented by the peak value of the signal on one side of its axis, a second channel for translating said signal with opposite polarity and including limiting means for passing only portions of said signal of lesser amplitude value than said predetermined shade value, rectifying means for deriving from said signal a background-illumination control-bias voltage proportional to said peak value of said signal, means for applying said bias voltage to said channels to stabilize the signals passed thereby, and means for combining the oppositely poled signal outputs of said channels, whereby said lesser value portions of said signal are at least partially suppressed, and means for adjusting said limiting means to adjust said predetermined value, thereby to set the black level of the combined signal at any desired tone value.

9. A television video-frequency signal-translating system for suppressing portions of a translated video-frequency signal of lesser amplitude values than that corresponding to a predetermined shade value thereof comprising, a first channel including an output circuit for translating a signal with one polarity, means for applying to said channel a signal including video-frequency components occurring during predetermined trace-scanning periods and block-out components occurring during retrace-scanning periods and having lesser amplitude values than said video-frequency components, said channel including means for providing a stabilized signal in said output circuit, a second channel including an output circuit for translating said signal with opposite polarity, means for applying said video-frequency signal to said second channel, said second channel including means for providing a stabilizing signal of opposite polarity in its output circuit and limiting means for passing only portions of said signal of lesser amplitude values than that corresponding to said video-frequency components, and means for combining the oppositely-poled unidirectional signal outputs of said channels including background components, whereby said lesser amplitude value portions of said signal are at least partially suppressed.

10. A television video-frequency signal-translating system for suppressing portions of a translated video-frequency signal of lesser amplitude values than that corresponding to a predetermined shade value thereof comprising, a first channel including an output circuit for translating a signal with one polarity, means for applying to said channel a signal including video-frequency components occurring during trace-scanning periods and block-out components occurring during retrace-scanning periods and having lesser amplitude values than the amplitude values of said video-frequency components corresponding to black, said channel

including means for providing a stabilized signal in said output circuit, a second channel including an output circuit for translating said signal with opposite polarity, means for applying said video-frequency signal to said second channel, said second channel including means for providing a stabilized signal of opposite polarity in its output circuit and limiting means for passing only portions of said signal of lesser amplitude values than that corresponding to black, and means for combining the oppositely-poled unidirectional signal outputs of said channels including background components, whereby said portions of said signal of lesser amplitude values than said value corresponding to black are at least partially suppressed to establish a predetermined black level for said signal.

11. A television video-frequency signal-translating system for suppressing portions of a translated video-frequency signal of lesser amplitude values than that corresponding to a predetermined shade value thereof comprising, a first channel including an output circuit for translating a signal with one polarity, means for applying to said channel a signal including video-frequency components occurring during trace-scanning periods and block-out components occurring during retrace-scanning periods and having lesser amplitude values than the amplitude values of said video-frequency components corresponding to black, said channel including means for providing a stabilized signal in said output circuit, a second channel including an output circuit for translating said signal with opposite polarity, means for applying said signal to said second channel, said second channel including means for providing a stabilized signal of opposite polarity in its output circuit and limiting means for passing only portions of said signal of lesser amplitude

values than that corresponding to said predetermined value corresponding to black, means for combining the oppositely-poled unidirectional signal outputs of said channels including background components, whereby said portions of said signal of lesser amplitude values than said value corresponding to black are at least partially suppressed to establish a predetermined black level for said signal, and means for adjusting said limiting means to adjust said predetermined value, thereby to set the black level of the combined signal at any desired tone value of the signal.

12. A television video-frequency signal-translating system for suppressing portions of a translated video-frequency signal of lesser amplitude values than that corresponding to a predetermined shade value thereof comprising, a first channel including an output circuit for translating a signal, means for applying to said channel said signal with such polarity that an increase in signal-amplitude value corresponds to a decrease in shade values, said channel including means for providing a stabilized signal in said output circuit, a second channel including an output circuit for translating said signal with opposite polarity, means for applying said video-frequency signal to said second channel, said second channel including means for providing a stabilized signal of opposite polarity in its output circuit and limiting means for passing only portions of said signal of lesser amplitude values than that corresponding to said predetermined shade value, and means for combining the oppositely-poled unidirectional signal outputs of said channels including background components, whereby said lesser amplitude value portions of said signal are at least partially suppressed.

HAROLD M. LEWIS. 40
